PLAYGROUND EQUIPMENT BASE

Ronald L. Ewers, 796 Anderson Road, Litchfield, Mich.
49252, and William F. McCombs, 4145 Parklawn Ave.,
Edina, Minn. 55435

Filed Mar. 3, 1975, Ser. No. 554,412

Term of patent 14 years

Int. Cl. D21—03

U.S. Cl. D34—5 L

FIG. 1

FIG. 2

FIG. 3

FIG. 4

FIG. 5

FIG. 1 is a view in perspective of a playground equipment base showing our new design;

FIG. 2 is a view in side elevation thereof, the side opposite that shown being a mirror image;

FIG. 3 is a view in side elevation thereof rotated ninety degrees with respect to FIG. 2, the side opposite that shown being a mirror image;

FIG. 4 is a view in top plan thereof; and

FIG. 5 is a view in bottom plan thereof.

We claim:

The ornamental design for a playground equipment base, substantially as shown and described.
